TROUSERS HANGER

Edward L. Blackman, New York, N. Y.

Application January 17, 1951, Serial No. 206,499

2 Claims. (Cl. 223—96)

1

The invention relates to hangers for trousers and skirts and more particularly to a hanger specially provided to maintain an even pressure on the cuffs of trousers, or the waist of a skirt, to prevent undue creases from the pressure and promote the smoothing out of undesirable wrinkles formed in usage.

One of the objects of this invention is the provision of a trousers hanger into which the cuffs of the trousers may be clipped in place evenly and automatically by the exertion of an upward pressure without the necessity of using one hand or a portion of the body for applying or releasing hanger tension as has heretofore been necessary with this type of device.

Another object of this invention is to provide a trousers holder which exerts an even tension over the trousers or skirt thus preventing wrinkles from forming from uneven pressure.

Another object of this invention is the provision of a wide frictional surface for holding the trousers or skirt so that a considerable pressure, if needed, may be exerted at the opposite or waist end of the trousers to facilitate the removal of undesirable wrinkles.

Other objects and advantages will be apparent from the specification and drawings in which:

Fig. 1 is a side elevation of the hanger in open position;

Fig. 2 is a top view of a closed hanger with a pair of trousers clamped therein;

Fig. 3 is a side view of the clamp locking mechanism;

Fig. 4 is a side elevation of a hanger in closed position;

Fig. 5 is an end elevation of a hanger in open position.

Referring to the drawings, 1 is a clothes bar, such as is common in most closets. The main back board 2 of the hanger is preferably composed of wood, although any suitable material may be used such as plastic or metal. The back board 2 has affixed to its top, by any suitable means, hooks 3 and 3a bent to engage the bar 1 for suspension of the back board 2 therefrom. Attached to the back board 2 at 4 and 4a by means of screws are spring pieces 5 and 6 whose rearward ends are turned sharply upward to form spring release abutments 7 and 8 and whose forward portions are gradually turned upward at 9 and 10, then sharply downward as at 11 and 12 and spread out to form spade shaped clamps 13 and 14 having bottom edges rolled as at 15 and 16. These rolled bottom edges are for the purpose of offering little resistance to the insertion of the cuffs 17 of trousers 18 into the clips 13 and

2

14. The parts 9 and 10 form stops which prevent the over insertion of the bottoms of trousers when inserted into the device.

At one side of the back piece 2 is attached a front board 19 by means of hinges 20 and 21. The front piece is inset slightly toward the top as at 22 to conform with the thickness of the cloth of the trouser cuff 17 and on the inset has carved out depressions 23 and 24 corresponding in depth and size to the clips 13 and 14 and spaced so that when the front board is closed on the back board by swinging on the hinges 20 and 21 the clips 13 and 14 fit closely into the depressions 23 and 24. The inset portion of the front board 19 is cut out as at 25 for the purpose of providing a non-pressure area at that portion of the cuff 17 corresponding to the back or heel portion of the cuff it being undesirable to maintain pressure on this portion, although in some cases it may be preferable to omit this cut out 25 if pressure is desired along the entire cuff and make the front board complementary in size to the back board 2.

At the end of the front board 19 is a spring latch 26 affixed to the front board by screws 27 and 27a or by other suitable means. The latch has a catch opening 28 adapted to lock into a stud 29 for the purpose of keeping the boards 2 and 19 in closed position when the opening 28 engages the stud 29.

At the top of the front board 19 are suitably affixed at 30 and 31 two forwardly and upwardly thrust spring release arms 32 and 33 for the purpose of making contact with the spring release abutments 7 and 8 respectively. The arm 33 is slightly shorter than the arm 32 so that in closing the front board 19 on the back board 2 pressure will be applied by 32 and 33 on 7 and 8 respectively at approximately the same time thus preventing a premature release of pressure on the trouser cuff at the grip 13.

In operation the pants are folded in alignment then the cuffs are slid under the spade like clamps 13 and 14. Their spring pressure being enough to hold the trousers in position, the front board 19 is now swung closed on the back board 2 by means of the hinges 20 and 21 and at the last closing movement the abutments of the arms 32 and 33 strike the abutments 7 and 8 of the back board causing the spade-like clamps to release some of their pressure and form a continuous flat surface of approximately even pressure with the front board, so that the pants are held tightly by a smooth surface both at the front and rear except for the heel portion of the cuff which is allowed freedom by reason of the indentation 25.

While in this position a slight weight could be applied to the waist of the trousers in order to help smooth out any wrinkles between the hanger and the waist. It has been found that due to the resiliency of the wooden back board and due to the slight release of pressure necessary, that the projections 32 and 33 will rock slightly on the ends 7 and 8 backwards pushing out the clamps 13 and 14, thus releasing the clamping pressure. These parts will also return to normal on release of contact between the ends 7, 8, and 32, 33. This is especially true if the screws are not turned down completely tight on the back board.

I do not wish to restrict my invention to the specific form shown as the back board may be attached to or be a part of the horizontal section of an ordinary coat hanger so that a coat may be placed over the trousers, or may be made as an added part of a coat hanger.

What I claim is:

1. In a trouser hanger of the character described, a base support having spring clamps with clamp release projections semirigidly attached to said base support, a complementary support swingably attached by a hinge to said base support, having indentations conforming approximately to the shape of said clamps on said base support, forwardly projecting clamp release means on said complementary support adapted to contact said clamp release projections on said spring clamps and release tension therefrom when said complementary support is in proximal

contact with said base support, a latch for maintaining said base support and said complementary support in proximity the one with the other.

2. In a trouser hanger of the character described, a base support having spring clamps with clamp release projections semirigidly attached thereto for contact with and retention of a pair of trousers, a complementary support hingedly attached to said base support at one edge, and having indentations conforming to the shape of said clamps on said base support, upwardly and forwardly projecting clamp release means on said complementary support adapted to positively contact the projections on said spring clamps and reduce tension therefrom whereby said clamps and said complementary support become integrated when said complementary support is in proximal contact with said base support, a latch for maintaining said base support and said complementary support in proximity, suspension means for said base support and complementary support and a cutaway portion on said complementary support for release of pressure on said trousers at one side thereof.

25. EDWARD L. BLACKMAN.
